UNITED STATES PATENT OFFICE.

FRANK VAN DUZEN, OF MARION, OHIO.

EXHAUST-MUFFLER FOR ENGINES.

SPECIFICATION forming part of Letters Patent No. 638,776, dated December 12, 1899.

Original application filed August 18, 1898, Serial No. 688,920. Divided and this application filed February 25, 1899. Serial No. 706,820. (No model.)

To all whom it may concern:

Be it known that I, FRANK VAN DUZEN, a citizen of the United States, and a resident of the city of Marion, in the county of Marion 5 and State of Ohio, have invented certain new and useful improvements in exhaust-mufflers for engines operated by the explosion of gas, gasolene, kerosene, and other coal-oils and hydrocarbons, of which the following is a 10 specification.

My invention relates to improvements in muffling apparatus and the mode of operating the same.

The invention herein set forth was contained in an application for Letters Patent of the United States filed by me on August 18, 1898, in the Patent Office of the United States, which application bore the serial number 688,920. A division of said application having been required by the Commissioner of Patents, the invention first aforesaid has been transferred to this specification.

The several features of my invention and the various advantages resulting from their 25 use conjointly or otherwise will be apparent from the following description and claim.

In the drawings illustrating my invention I have shown it in connection with that kind of a cylinder which has one open and one 30 closed end, the moving power or impulse acting on one side of the piston—viz., between the piston and the closed head of the cylinder.

In the accompanying drawings, making a part of this application, and in which similar 35 letters of reference indicate corresponding parts, Figure 1 shows in elevation means of my invention for muffling the sound of the discharge of the gases passing from the engine and also shows in elevation certain portions of one of the various kinds of engines to which my invention can be applied. Fig. 40 2 is a vertical section through the muffling apparatus and the exhaust-passages, cylinder, and connection-rod, but showing in elevation the crank-arm and a part of the fly-wheel. Fig. 3 is a top view of the muffler-chamber, valve, valve-rod, lever, and a portion of the rod for operating this lever. Fig. 45 4 is a section of one of the concentric cylinders of the mufflers, illustrating how the latter are perforated.

The cylinder A is shown provided with the usual water-jacket A². A³ indicates the cylinder-head. (Shown in Fig. 1, but omitted in Fig. 2.) E¹⁴ indicates the piston, slideable within cylinder A. The crank-shaft E⁹ of the engine carries a fly-wheel E⁸, the latter being shown in solid lines in Fig. 1 and in dotted lines in Fig. 2. The crank E¹⁰ is rigidly connected at one end to the shaft E⁹ and at the other end carries the customary crank-arm E¹², to which latter one end of the connecting-rod or pitman E¹³ is pivotally connected. The other end of this connecting-rod E¹³ is pivotally connected to the pivot-shaft E¹⁵ of the 65 piston E¹⁴. The mode in which these parts operate is obvious and well known.

As the noise caused by the first explosion (or exhaust) of the engine, and, indeed, of the successive exhausts, may be disagreeable and 70 in many cases be undesirable, particularly in frightening horses on the road or elsewhere when the same is used for traction or portable purposes, it becomes desirable to provide means for deadening the sound of the exhaust on such occasions. Such means are as follows: As the exhaust-gases pass through the exit-port J of the engine and through the passage J² as soon as valve J² is opened by suitable means I conduct them into a muffler-receptacle K by connecting the passage J² to the muffler-shell. Between the end K² and the end K³ are a series of concentric cylinders K⁴, each outer one larger than the preceding and a space K⁵ being between each 75 cylinder and the next one. These cylinders are held in place by the end K² and the end K³. Through one cylinder near its top is a row of perforations K⁶, and near the bottom of the next cylinder is a row of openings K⁶, 80 and so on, alternating until the outer cylinder is reached, and then the final exit-holes K⁷ are in the end K² or the end K³, preferably in the latter. The end K³ has a valve K⁸ fixed to and hung on a rod K⁹, journaled 85 in eyes or bearings K¹⁰ on the top of the muffling vessel. There is a lever K¹¹ connected rigidly at one end to the rod K⁹ and at the other end pivotally connected to the end of a pull rod or rope K¹², preferably the 90 former, and to enable this to be set at a desired point there are notches in the rod adapt-

ed to engage a stud K¹¹, (see dotted lines, Fig. 1,) located on a fixed portion of the apparatus. By moving the rod K¹³ in one direction the valve or damper K⁸ is opened, thus allowing the products of combustion to go directly out into the open air by passing through the central portion of the muffler. In such event the exhaust has its full resonance of sound and the engine has its full working power, as there is no back pressure on the exhaust. By moving the rod K¹³ in the opposite direction the damper K⁸ is closed and the gases of the exhaust are compelled to travel through the holes K⁶ of the cylinders and the spaces K⁵ between them and the outlet-holes K⁷, thereby breaking up and silencing the roar attendant upon the exhaust when allowed to escape directly from the engine.

What I claim as new and of my invention, and desire to secure by Letters Patent, is—

In an engine, the combination of an exhaust, and a muffler consisting of concentric cylinders, with holes alternately at adjacent ends, and held between plates, one of which has a hole of exit, the central passage of the muffler being in connection with the exhaust, and a valve for closing this passage into the open air, and compelling the products of the exhaust to go through the muffler, the valve and the operating-rod K⁹ rigid with said valve and a lever K¹² fixed thereto, and at its other end pivotally connected to a rod K¹³, the rod having detents and a stationary detent for engaging any one of the detents of the rod, substantially as and for the purposes specified.

FRANK VAN DUZEN.
